UNITED STATES PATENT OFFICE

GEORGE GREGORY SMITH AND GEORGE GARNET STOUP, OF FRANKLIN, VIRGINIA

AUTOMOBILE JACK

Application filed September 26, 1927. Serial No. 222,059.

Our invention relates to the art of lifting jacks and it particularly has for its object to provide a jack of the mechanically actuated type that will be especially useful with autos having balloon tires. The axles of machines equipped with balloon tires are disposed closer to the ground, when a tire is flat, than is the case where the old style high pressure tires are used. Consequently, most lifting jacks heretofore designed are unsuitable for use with cars having balloon tires, since it is almost impossible to place such jacks beneath the axle, when the tire is flat. This difficulty we have sought to overcome 15 with the jack constituting our present invention.

Further the invention has for its object to provide a low jack with the highest possible lift. Another object is to provide a jack 20 of the lever-pawl-and-ratchet type, in which the lever and pawl are located as near the upper end of the jack standard as possible.

Further it is an object to provide a jack 25 with a spring actuated pawl and means to hold the pawl yieldingly in a disengaging position, when it is desired to lower the jack, and to provide the jack operating lever with a device by which it can be made to move the pawl into engagement with the ratchet at will 30 in using the lever as a lowering member.

Further the invention has for its object to provide a jack in which the lever is linked to a fixedly located pivot, the lever being pivoted to the link, thereby giving increased 35 leverage. Still further the invention has for an object to provide a jack with a hinged foot that is held by an articulated brace and is provided with a foot operable device for "breaking" the joint of the brace to release 40 the pivot and permit the jack to rock over forwardly and release the auto readily.

Other objects will, in part, be obvious and, in part, be pointed out hereinafter.

To the attainment of the aforesaid objects 45 and ends, the invention resides in those novel features of construction, combination and arrangement of parts, all of which will be first fully described, then specifically pointed out in the appended claims, reference being had to 50 the accompanying drawings, in which:

Fig. 1 is a side elevation of our invention.

Fig. 2 is an enlarged detail front elevation (the lever being shown in section) of the upper portion of the jack.

Fig. 3 is a vertical longitudinal section of the parts shown in Fig. 2, taken approximately on the line 3—3 of Fig. 4.

Fig. 4 is a detail section on the line 4—4 of Fig. 3.

Fig. 5 is a detail side elevation of the lever 60 and its extension handle.

In the drawings, in which like numerals of reference indicate like parts in all of the figures, 1 represents the base upon which is rigidly mounted the hollow standard 2, which 65 has a portion removed near the upper end, as at 3, to leave an opening through which the ratchet bar is exposed.

4—4 indicates a pair of brackets extending from the standard 2 and terminating in 70 supporting ends 5, in which the primary fulcrum bolt 6 is located.

The standard 2 is chambered, as at 7, for the reception of the vertically movable ratchet bar 9 and it is provided with ribs 8 75 which enter slots 11 in the bar 9, in order to brace that bar, when it has been moved to its uppermost position, and prevent misalignment of the parts 2 and 9.

The ratchet bar 9 has teeth 10 and is also 80 provided with a swiveled head 12 for the usual purpose.

13 is a holding pawl which is pivotally mounted on the fulcrum bolt 6 and is normally held in spring pressed engagement 85 with the ratchet bar's teeth.

14 is the lever link member, which is fulcrumed on the bolt 6, and to which the lever 23 is pivoted, as at 22.

A second lever 15, serving as a spring tension lever, is fulcrumed on the bolt 6 and, at its upper end, is connected with a latch bar 16 that is adapted to be hooked on either of the studs 17 or 18 accordingly as to whether the pawl 13 is to be held in the ratchet engaged position or in the released position.

A spring 19 is coiled on the bolt 6 and has one end 20 engaged with the pawl 13 and the other end 21 engaged with the spring tension lever 15.

The operating lever 23 may be made in one piece or, preferably, it is provided with an extension handle 25 that is socketed on the tenon 24 and held with a suitable pin 26, or in any other convenient manner. The lever 23 has a toe portion 27 adapted to engage the teeth 10 of the ratchet bar 9 in lifting and lowering that bar. 28 is a pawl holding-in pin that is adapted, when it is desired to lower the ratchet bar, to be pressed against the pawl 13 to cause it to enter the teeth 10, as will be later more fully explained.

29 is the hinged section of the base 1, the section 29 being hinged at 32 to the standard 2 and is adapted to be folded up against that standard, when desired.

In order to retain the section 29 in alignment with the fixed section 1, I provide an articulated brace composed of the members 30—30 hinged at 31 and 33, respectively, and connected together by a hinged joint 34 having a stop 35 to limit motion in one direction; or, in other words, to provide a rule joint. In order to break the joint of the articulated brace 30—30, when it is desired to push the auto off the jack, I provide a foot engageable lever 36 pivoted at 37 and having a finger 38 to engage the under side of the brace 30 and move it to break the joint.

30 In order to prevent the pawl 13 from being moved too far back, when it is placed in the released position, see dotted lines Fig. 1, a back stop 39 is provided, see Fig. 4.

From the foregoing description, it will be 35 obvious that, in order to raise the ratchet bar 9 from the position shown in Fig. 3, the latch bar 16 is hooked on the stud 17, thus giving tension to the spring 19, so that it will tend to hold the pawl 13 in engagement with the 40 ratchet bar teeth. The lever 23 is then rocked on its fulcrums 22 and 6 with a downward motion, thereby elevating the toe portion 27 and raising the ratchet bar, this operation being repeated until the desired elevation of the ratchet bar has been acquired.

When it is desired to lower the ratchet bar, the operator hooks the latch bar 16 on the stud 18. This causes the spring tension to exert an action on the pawl 13, which, when 50 the pawl is released from the tooth, will move backward to the dotted position shown in Fig. 1. The operator then moves the lever 23 downwardly a slight distance, enough to release the pawl 13 from the teeth 10. Then, 55 while pushing in on the lever, he raises it, permitting the ratchet bar 9 to lower. Raising the lever 23, while pushing in on it, causes the pin 28 to press the pawl 13 back into engagement with the teeth 10 to hold the bar 9 in the position to which it has been lowered. The operator then pulls back on the handle, raises it and engages the toe portion 27 with a tooth 10 at a higher elevation and repeats the operation.

55 From the foregoing description, taken in

connection with the accompanying drawings, it is thought that the construction, operation and advantages of the invention will be clearly understood by those skilled in the art.

What we claim is:

1. A jack comprising a base, a standard having a chamber, a ratchet bar vertically movable in said chamber, said standard having an opening in one wall near the top to expose the ratchet bar, brackets carried by said standard, a primary fulcrum bolt mounted in said brackets, a pawl mounted on said bolt and adapted to project upwardly and be engaged with said ratchet bar, a lever carrying link member pivoted on said bolt, an operating lever pivoted to said link member and having a toe to engage said ratchet bar, and a spring device associated with said pawl, said pawl being bifurcated and mounted between said bracket, and said link member being located in the bifurcation of said pawl. 70 75 80 85

2. A jack comprising a base, a standard having a chamber, a ratchet bar vertically movable in said chamber, said standard having an opening in one wall near the top to expose the ratchet bar, brackets carried by said standard, a primary fulcrum bolt mounted in said brackets, a pawl mounted on said bolt and adapted to project upwardly and be engaged with said ratchet bar, a lever carrying link member pivoted on said bolt, an operating lever pivoted to said link member and having a toe to engage said ratchet bar, a spring device associated with said pawl, and means to adjust the tension of said spring device to either force said pawl toward said ratchet bar or hold it away from the same accordingly as said means is in one position or the other. 90 95 100

3. A jack comprising a base, a standard having a chamber, a ratchet bar vertically movable in said chamber, said standard having an opening in one wall near the top to expose the ratchet bar, brackets carried by said standard, a primary fulcrum bolt mounted in said brackets, a pawl mounted on said bolt and adapted to project upwardly and be engaged with said ratchet bar, a lever carrying link member pivoted on said bolt, an operating lever pivoted to said link member and having a toe to engage said ratchet bar, and a spring device associated with said pawl, said pawl being bifurcated and mounted between said bracket, said link member being located in the bifurcation of said pawl, and means to adjust the tension of said spring device to either force said pawl toward said ratchet bar or hold it away from the same accordingly as said means is in one position or the other. 105 110 115 120 125

4. A jack comprising a base, a standard having a chamber, a ratchet bar vertically movable in said chamber, said standard having an opening in one wall near the top to expose the ratchet bar, brackets carried by 130

- said standard, a primary fulcrum bolt mounted in said brackets, a pawl mounted on said bolt and adapted to project upwardly and be engaged with said ratchet bar, a lever carrying link member pivoted on said bolt, 5 an operating lever pivoted to said link member and having a toe to engage said ratchet bar, a spring device associated with said pawl, means to adjust the tension of said spring device to either force said pawl toward said ratchet bar or hold it away from the same accordingly as said means is in one position or the other, and a pawl engaging pin carried by said lever for the purposes specified. 10
5. A jack comprising a base, a standard having a chamber, a ratchet bar vertically movable in said chamber, said standard having an opening in one wall near the top to expose the ratchet bar, brackets carried by said standard, a primary fulcrum bolt mounted in said brackets, a pawl mounted on said bolt and adapted to project upwardly and be engaged with said ratchet bar, a lever carrying link member pivoted on said bolt, an 15 operating lever pivoted to said link member and having a toe to engage said ratchet bar, and a spring device associated with said pawl, said pawl being bifurcated and mounted between said bracket, said link member being 20 located in the bifurcation of said pawl, means to adjust the tension of said spring device to either force said pawl toward said ratchet bar or hold it away from the same accordingly as said means is in one position or the 25 other, and a pawl engaging pin carried by said lever for the purposes specified. 30
6. A jack comprising a base, a standard having a chamber, a ratchet bar vertically movable in said chamber, said standard having an opening in one wall near the top to expose the ratchet bar, brackets carried by said standard, a primary fulcrum bolt mounted in said brackets, a pawl mounted on said bolt and adapted to project upwardly and be engaged with said ratchet bar, a lever carrying 35 link member pivoted on said bolt, an operating lever pivoted to said link member and having a toe to engage said ratchet bar, a spring device associated with said pawl, means to adjust the tension of said spring device to either force said pawl toward said ratchet bar or hold it away from the same accordingly as said means is in one position or the 40 other, a pawl engaging pin carried by said lever, and a pawl back stop on one of said brackets for the purposes specified. 45
7. In a jack, an articulated base composed of two sections connected by a rule joint whereby normally to lie in one plane, a standard fixed with respect to one portion of said base, a ratchet bar mounted in said standard, means associated with said ratchet bar and said standard for raising and lowering said bar, an articulated one-way joint brace 50 between said standard and the other portion 55
- of said base, and a lever device distinct from said raising and lowering means to break the joint of the brace for the purposes specified. 60
